DOUGHNUT MACHINE

Stephen A. Gardner, Minneapolis, Minn., assignor
to Dough-King, Inc., Minneapolis, Minn., a cor-
poration of Minnesota

Application August 28, 1940, Serial No. 354,538

13 Claims.

(Cl. 53—7)

My invention relates to doughnut machines and has for an object to provide a doughnut machine which will be extremely efficient in operation.

Another object of the invention resides in providing a doughnut machine in which the doughnuts are progressed along a channel by means of the flow of the cooking liquid and in which the number of doughnuts passing through the machine is positively and accurately controlled to control the degree of cooking of the doughnuts.

Another object of the invention resides in providing a doughnut machine in which the capacity of the machine may be manually varied at will.

A still further object of the invention resides in providing cams for operating the doughnut former and the control device of the doughnut machine and in providing a construction for varying the capacity of the machine whereby a single cam of fixed form can be used for each of said devices.

An object of the invention resides in providing each of the cams for operating the doughnut former and control device with a number of irregularities, each irregularity forming a doughnut and controlling the passage of a doughnut along the channel and in providing means for preventing certain of the irregularities from effecting the operation of the doughnut former and control device.

Another object of the invention resides in providing spring controlled means for urging the cam followers operating in conjunction with the said cams into engagement therewith and in providing means for periodically rendering said spring controlled means inoperative.

Another object of the invention resides in providing a shaft having engaging members thereon adapted to engage parts movable with the cam followers for preventing movement of the followers toward the cam surfaces of the cams.

Another object of the invention resides in providing another cam adapted to be manually moved to engage or disengage a plurality of cam followers carried by the second shaft whereby said engaging members are brought into operative and inoperative positions at will.

A still further object of the invention resides in providing a doughnut machine adapted to operate at three different capacities.

A feature of the invention resides in employing two cam followers carried by the second shaft and in moving said cam to engage one or both of said cam followers or to clear both of said cam

followers for controlling the capacity of the machine.

Other objects of the invention reside in the novel combination and arrangement of parts and in the details of construction hereinafter illustrated and/or described.

In the drawings:

Fig. 1 is a plan view of a doughnut machine illustrating an embodiment of my invention.

Fig. 2 is a longitudinal elevational sectional view taken on line 2—2 of Fig. 1.

Fig. 3 is a plan sectional view taken on line 3—3 of Fig. 2.

Fig. 4 is a plan sectional view taken on line 15 4—4 of Fig. 2.

Fig. 5 is a view similar to Fig. 2 showing the parts in altered position.

Fig. 6 is an elevational sectional view taken on line 6—6 of Fig. 3.

Fig. 7 is a detail sectional view taken on line 7—7 of Fig. 2.

This invention is an improvement of my patent for Doughnut machine, No. 2,207,584, issued July 9, 1940, and the construction of parts not shown in detail in this application may be had from the said patent.

In the drawings I have shown a doughnut machine A which consists of a case 10 constructed with end walls 11 and 12 and side walls 13 and 14 connected therewith. The case includes uprights 15 at the corners of the same which extend throughout the height of the case and to which the various walls are attached. The walls are preferably constructed of sheet metal and are directly secured to the uprights 15. The case 10 further includes upper and lower frames 17 which are channel-shaped in cross section and which extend perimetricaly about the case and hold the various uprights 15 in position. The 40 walls of the case are also attached to these frames.

Within the case 10 is disposed a cooking kettle 18 which is preferably of cast metal and which is constructed with a bottom 19 and with vertical walls 21 extending upwardly therefrom. The vertical walls are connected at their upper ends with upper walls 22 and the various walls and bottom are so arranged as to form a channel 23 which extends throughout the major portion of the kettle and which provides a way along which the doughnuts may travel. The kettle 18 has one corner of the same removed, as designated at 24, leaving a main portion 25 of the width of the case 10 and of a length equal to about two-thirds of the length of the same. This construction pro-

vides an extension 26 to the kettle which extends up to the end wall 12. The case 10 is constructed with a ledge 27 extending about the margin of the same. A guard 29 on the case 10 issues upwardly from the walls thereof and overlies the edge of the ledge 27. The kettle 18 is supported on the frame 17 in any suitable manner.

The channel 23 is arranged to provide a straight run 32 which starts in close proximity to wall 12 and follows along wall 13. Channel 23 at the end of run 32 makes a curve 33 which leads into another straight run 34 following along the wall 11. At the end of this run the channel has another curve 35 which leads into still another straight run 36 which follows along the wall 14. At the end of the run 36 the channel is constructed with a loop 37 which is connected to another straight run 38. The run 38 terminates in a curve 39 which, in turn, is connected to a short straight run 41 parallel with the run 34 and closely positioned relative thereto. This run is connected to a curve 42 which, in turn, is connected to a straight run 43 parallel with the run 32 and disposed in close proximity thereto. The run 43 discharges into a reservoir 44 which is merely an enlargement of the said run. From this reservoir a short run 45 is provided which is connected by a curve 46 with the end of the run 32.

The major portion 25, of kettle 18, is enclosed by means of a hood 47. This hood utilizes the uprights 15 at the end wall 11 and two other uprights 48 which are attached to the case 10 at the locality of the end of the major portion 25 of the kettle formed by the corner 24. Between the various uprights are provided glass panels 49 which are slidably supported in guides 51 whereby the said panels may be removed. The hood 47 includes a top by means of which the major portion 25 of kettle 18 is enclosed and which has not been shown in the drawings.

In the reservoir 44 is provided a vertical tubular duct 52 which communicates at its lower end with the bottom of the reservoir 44. In this duct is disposed a propeller or elevator 53 which is mounted on the armature shaft of a motor 54. The duct 52 communicates at its upper end with the run 45 of the channel 23, thus discharging the cooking liquid from the reservoir 44 and into the run 45 of the channel, from which it flows throughout the course of the channel and is returned into the reservoir.

Situated at the beginning of the run 32 of channel 23 is a doughnut former 55 which comprises a receptacle 56 for dough and a cutter 57 connected therewith. Such construction being well known in the art will not be described in detail in this application. The cutter 57 includes a flanged sleeve 58 which severs dough extrusions from the mass contained in the receptacle 56. This sleeve is reciprocated in a vertical direction by means of a forked arm 59 which is mounted on a rock shaft 61. Rock shaft 61 is journaled at one end in a bearing 62 attached to frame 17, and at its other end in a manner to be presently more fully described. The forked arm 59 swings freely on the shaft 61 but may be locked in relation thereto by means of clutch 63.

Air pressure is provided in the upper portion of the receptacle 56 which forces the dough downwardly through the cutter and as the sleeve 58 is reciprocated, annular dough extrusions are deposited in the cooking liquid in the beginning of the run 32 of channel 23.

In the run 36 of channel 23 is arranged a

twisted tubular turner 65. This turner inverts the doughnuts after the same have been cooked a predetermined time so that the doughnuts may be cooked equally on both sides. Such construction being well known in the art will not be described in detail in this application. It is to be noted, however, that the turner 65 inclines in the direction of flow of the cooking liquid so that the bottom 19 of the kettle 18 at the run 41 is considerably lower than at the run 34.

In the run 43 of channel 23 is disposed an ejector 66 for removing the cooked doughnuts from the cooking liquid. This ejector comprises a shaft 67 which is constantly driven in a manner to be presently described in detail. This shaft has mounted on it, oppositely extending cranks 68 and 69. Sets of toothed blades 71 and 72 are mounted on the said cranks and are adapted to be alternately raised and lowered and also moved in a longitudinal direction as the shaft 67 rotates. The lower ends of these blades slide upon an inclined rest 73 which is mounted on the bottom 19 of kettle 18 in the portion of the run 43 leading from the curve 42. It will readily be comprehended that, as the doughnuts reach the said blades the doughnuts are elevated and progressed upwardly and outwardly of the kettle 18. The ejector 66 is disposed within a trough 74 constructed with two side plates 75 and 76 and a bottom 77 connected therewith. The said trough extends outwardly beyond the wall 12 of the case 10 and directs the doughnuts out of the machine.

For controlling the rate of travel of the doughnuts along the channel 23, two control devices 78 and 79 are employed. These control devices operate to allow the doughnuts, one at a time, to enter the turner 65 and the ejector 66, whereby the degree of cooking of the doughnuts on both sides may be controlled. The control device 78 is situated in the run 34 of channel 23, while the control device 79 is situated in the run 41 of channel 23.

Inasmuch as the control devices 78 and 79 do not form any particular feature of the instant application for patent, the said devices have not been shown in detail in the drawings and the same will not be described, reference being had to the Patent issued to Alexander S. T. Lagaard for Doughnut machines, Number 2,207,546. It will be noted, however, that the control device 78 is operated by a shaft 112 and that the control device 79 is operated from the control device 78 through the same shaft. It will be noted that each control device rocks alternately in one direction and then in the other direction to allow the doughnuts, one at a time, to pass said device. This is accomplished by periodical oscillation of the shaft 112 which is procured in a manner to be subsequently more fully described.

In order to procure sufficient cooking time for the doughnuts in advance of each control device, when the machine is first started, it becomes necessary to prevent travel of the doughnuts until the desired number of doughnuts are in the machine. For this purpose the two control devices 78 and 79 may be independently disconnected from or connected to the shaft 112 by clutch devices, not shown, which are operated by means of operating rods 291 and 292 which extend outwardly of the machine and have knobs 293 at their outer ends.

The cutter 55, the ejector 66, and the two control devices 78 and 79 are all operated by an operating mechanism 140 contained within a

chamber 167 formed within a case 144, disposed in the cut-away corner 24 of the kettle 18. This operating mechanism will now be described in detail.

The case 144 includes a lateral wall structure indicated in its entirety by the reference numeral 145 which is open at the top and bottom. This wall structure includes two side walls 148 and 147 and two end walls 148 and 149. These walls are covered at the top by a cover 151 which is secured to said walls by means of counter-sunk screws 152 threaded into bosses 153 formed on said walls. In a similar manner a closure 154 is provided for a lowermost portion of the case 144, which closure is attached to the wall structure 145 by means of screws 155 which are similarly threaded into bosses 156 formed on the wall structure 145. The case 144 is provided with pads 157 formed on the closure 154, which pads rest upon the upper frame 17 and are secured thereto by means of screws 158 which pass through the uppermost flanges of the frame members of frame 17 and are threaded into said pads.

The closure 154 of case 144 has attached to the underside thereof an electric motor 159 having a vertical shaft 161. Motor 159 is constructed with an end bell 162 provided with a flange 163 adapted to engage a ring 164 cast on the under surface of the closure 154. Screws 165 extending through the flange 163 are threaded into the ring 164 and hold the motor 159 attached to the closure 154. Motor 159 may be of any desirable construction and the details thereof have not been shown in the drawings. The shaft 161 of motor 159 passes through a seal 166 and into the chamber 167 formed within the case 144.

Issuing from the wall 147 of case 144 are two bearing supports 168 and 169. The bearing support 168 has attached to it a bearing 171 for the lower end of a vertically extending shaft 172. This shaft is journaled in its upper end in a ball bearing 173 which serves as an end thrust bearing for restraining longitudinal movement of the shaft 172. Shaft 172 has secured to the lower end thereof a spur gear 174 which meshes with a pinion 175 fast on the shaft 161 of motor 159. Shaft 172 also has formed on it a worm 176 which meshes with a worm wheel 177 keyed to a horizontally extending shaft 178. Shaft 178 extends completely across the case and is journaled in bearings 181 and 182 carried by the end walls 148 and 149.

The ejector 66 is driven from the shaft 172 in the following manner: Shaft 67 of the said ejector extends through a tubular housing 183 provided with a flange 184 at one end. This flange is secured to the wall 149 of case 144 by means of screws 185. The housing 183 is provided at its outer end with a bearing 186 which journals one end of the shaft 67. The other end of this shaft extends into the chamber 167 of case 144 and is journaled in a bearing 187 issuing outwardly from the wall 147 of case 144. The shaft 67 has mounted on it a spiral gear 188 which meshes with another spiral gear 189 fast on the shaft 172. These gears are so proportioned that the shaft 67 travels at a suitable speed to alternately raise the toothed blades 71 and 72 and procure ejection of the doughnuts.

The mechanism for operating the control devices 78 and 79 will now be described in detail. Connected to the shaft 172 by means of a universal joint 193 is a floating shaft 114. This shaft is connected by means of a universal joint 75

115 with another shaft 116 extending through the wall 148 of the case 144 and into the chamber 167. Within the chamber 167 of case 144 is formed an elongated boss 213 which is provided with bearings 220 journaling the shaft 116. This shaft has secured to the end of it a bevel gear 215 which meshes with another bevel gear 216 fast on a shaft 217 extending horizontally across the case 144. The latter shaft is journaled in bearings 218 carried by the side walls 148 and 149 of the case 144 and shown in Fig. 4.

Attached to the wall 148 of case 144, near the uppermost portion of the same, as best shown in Fig. 6, is a stud 219. Mounted for oscillation on this stud is a lever 221 which has a depending arm 222. Arm 222 is formed with a gear segment 223 which meshes with a pinion 224 rigidly secured to the shaft 217. The lever 221 is further formed with an arm 225 which carries at the end of it a roller 226 adapted to engage the surface 227 of a disc cam 228. Cam 228 is keyed to the shaft 178 and is best shown in Fig. 6. The cam 228 which operates the control devices 78 and 79 has three depressions 272 in it, by means of which the control devices may be operated three times for each revolution of the shaft 178.

The lever 221 is urged to move in a counter-clockwise direction, as viewed in Fig. 6, to cause the roller 226 to bear against the cam 228 by means of the following construction: Issuing inwardly from the wall 147 of case 144 is a boss 231 which is bored at 232 to slidably receive a tubular spring housing 233. Tubular spring housing 233 has connected to the end of it a socketed head 234 which has secured to it a forked arm 235. Arm 235 is pivoted by means of a pintle 236 to the arm 222 of lever 221. Within the interior of the housing 233 is mounted a compression coil spring 237 which is seated at one end against the head 234. A plug 245 is screwed into the boss 232 and engages the other end of the spring 237. It will be readily comprehended that the spring 237 urges the roller 226 to follow the surface 227 of cam 228. In the event that the spring 237 should break, plug 245 may be removed from the exterior of the device and the spring may be removed from the housing 233. A new spring may then be inserted and the plug 245 screwed into the boss 231.

For rocking the shaft 61 which operates the cutter 55, the following construction is used: Shaft 61 is connected by means of a coupling 191 with another shaft 192 extending across the walls 148 and 149 of case 144. This latter shaft is journaled in bearings 193 and 194 carried by the walls 148 and 149 of the case. The shaft 192 has keyed to it a bell crank 195 (Fig. 5) which has an upwardly extending arm 196 and a substantially horizontally extending arm 197. The arm 197 of bell crank 195 has rotatably mounted at the end thereof a roller 198 which is adapted to engage the periphery 199 of a disc cam 201. Cam 201 is constructed with a hub 202, Fig. 4, which is keyed to the shaft 178. The surface 199 of cam 201 is formed with three indentations 204 disposed 120 degrees apart which, when the roller 198 drops into the same, permit the bell crank 195 to oscillate, whereby the cutter sleeve 58 is raised and lowered to procure the deposit of three dough formations into the cooking liquid in the kettle 18 for each revolution of shaft 178. The roller 198 is urged into engagement with the surface 199 of cam 201 by means of a spring similar to that described in connection with the mechanism for operating the con-

tral devices. This spring is contained within a tubular housing 206 slideable in a boss 207 issuing from the wall 147 of case 144. The said spring acts against a head 208 which is pivoted to the end of the arm 196 of bell crank 195 by means of a pin 210 and urges the same to cause a clockwise movement of shaft 192, as viewed in Fig. 5.

By means of the construction now to be described, and which constitutes the instant invention, operation of the cutter and control devices may be procured by means of two or three of the depressions of the cams referred to so that the machine may be operated at full capacity, two thirds capacity or one third capacity. Extending across the walls 148 and 149 of the housing 144 is a shaft 190. This shaft is journaled in two bearings 92 carried by the walls 148 and 149 of the case 144. The shaft 190 has secured to it two arms 94 and 95, best shown in Figs. 4 and 6, which extend beneath the two spring housings 233 and 206. Each of these spring housings has a lug 96 welded or brazed thereto which is constructed with a face 97 facing in the direction of the two cams 228 and 201. The arms 94 and 95 are constructed with hooks 98 which, when the shaft is rocked, are adapted to engage the surfaces 97 of the lugs 96 and to restrain movement of the springs within the same. This holds the two cam followers 226 and 198 from engagement with the respective cams 228 and 201 and prevents the said cam followers from following the depressions in said cams while the spring housings are so engaged.

The shaft 91 is urged into the position shown in Fig. 6 by means of a spring 99, similar to the spring 237, which spring is contained in a spring housing 101 attached to the wall 147 of case 144, which is best shown in Fig. 2. This spring engages a plunger 102 slideable in the housing 101 and is pivoted to an arm 103 keyed on shaft 190. Arm 103 has a stop 104 on the same which engages wall 147 and limits the movement of shaft 190 to its position in which the arms 94 and 95 are situated, as shown in Fig. 4.

The shaft 190 is rocked in its bearings in the following manner: Attached to the said shaft is an arm 105 which is provided with two cam followers in the form of rollers which are indicated at 106a and 106b. These rollers are adapted to engage a cam 107 slidably mounted on the shaft 178. Cam 107 is constructed with a single projecting portion 108 having an arcuate cam surface 109 of an extent approximately 120 degrees. The rollers 106a and 106b are situated so that both rollers at one position will rest upon the projecting portion 108. Cam 107 has a pin 281 secured to it which passes through a hole 282 in the cam 201 (Fig. 4). By means of this construction, the cam 107 is keyed relative to the shaft 178 and may move axially with respect thereto. As will be noted in Fig. 3 the roller 106a is longer than the roller 106b so that either the roller 106a or both the rollers may be made to engage the surface of the cam 107. The cam 107 is shifted longitudinally by means of the following construction: Extending downwardly from the cover 151 is a boss 284 which is drilled to form a bearing for a shaft 285, best shown in Fig. 2. Shaft 285 extends outwardly beyond the cover and has secured to it a finger piece 286 by means of which the said shaft may be rotated. Shaft 285 also extends below the boss 284 and has secured to its lower end a plate 287. This plate has attached to it in off-set relation with respect

to the shaft 285 a rod 289. Rod 289 has secured to the end of it an arm 271 which has attached to it a pin 288. Pin 288 is adapted to engage within a groove 272 in a hub 275 formed on cam 107. When the shaft 285 is rotated through engagement with finger piece 286, pin 272 shifts the hub 275 along the shaft 178. At one extreme position of the cam both cam rollers 106a and 106b engage the cam surface of the cam. At the other extreme position of the cam neither of the cam rollers engage the cam. In an intermediate position of the cam only the roller 106a engages the cam. The hub 275 is held in adjusted position by means of a construction shown in detail in Fig. 7. Formed on the cover 151 is a boss 276 which is provided with a bore 277. In this bore is disposed a ball 278 which is adapted to engage any of a number of depressions 279 in the upper surface of the plate 287. This ball is yieldingly urged into engagement with the plate 287 by means of a compression coil spring 261 disposed in bore 277 which is seated at one end against the ball 278 and at its other end against a cap 262 secured to the cover 151 by means of screws 263.

The operation of my invention is as follows: When the machine is first to be used the motor 183 is energized which procures travel of the cooking liquid along the channel 23. Actuation of the motor 159 causes the shaft 178 to rotate and the ejector 66 is placed in operation. If the finger piece 286, which is attached to shaft 285, is rotated in one direction, cam 107 is moved out of engagement with either of the rollers 106a or 106b. The two hooks 98 are then forced downwardly through the spring 99 and are free from the lugs 96. Both the cutter 55 and the control devices 78 and 79 are then operated each time the cam rollers 226 and 198 engage the cams 228 and 201 with which they cooperate. Thus three doughnuts are produced and the travel thereof along the machine controlled for each operation of shaft 178. If the cam 107 is moved to an intermediate position, the same may be caused to engage only the roller 106a, and clearing the roller 106b. The roller 106a and the projecting portion 108 of cam 107 are so situated that the arm 105 is raised when the cam rollers 226 and 198 are in position to engage one of the irregularities of the cams with which they cooperate. Thus the hooks 98 are brought into engagement with the lugs 96 and the said cam followers prevented from functioning. As soon as the roller 106a passes the portion 108 of cam 107, the two cam followers 226 and 198 are free to engage the other two irregularities of the respective cams with which they cooperate. Thus two instead of three doughnuts are produced with each revolution of the shaft. When the cam 107 is shifted to its other extreme position, both rollers 106a and 106b are brought into the path of travel of the cam 107. The distance apart of the roller 106a and 106b circumferentially and the circumferential extent of the portion 108 of cam 107 is sufficient so that both cams may ride upon the surface 109 of said portion of the cam at the same time. It will thus be seen that the two cams cause engagement of the hooks 98 with the lugs 96 throughout movement of two of the irregularities of each of the cams 228 and 201 with respect to the cam rollers. Thus only one doughnut is produced per revolution of the shaft 178. It will hence become obvious that the machine may be adjusted to operate at full capacity, two-thirds capacity, or one-third capacity, by merely

shifting the position of the cam 107 to any of three positions.

The advantages of my invention are manifest. My improved doughnut machine is extremely positive in operation. The operating mechanism of my invention is simple and eliminates the need of variable forms of cams. With my invention the capacity of the machine may be easily and quickly varied. With my invention it is possible to procure one of three capacities.

Changes in the specific form of my invention, as herein disclosed, may be made within the scope of what is claimed without departing from the spirit of my invention.

Having described my invention, what I claim as new and desire to protect by Letters Patent is:

1. In a doughnut machine in which the doughnuts are progressed along a way, a doughnut former for depositing dough formations in the cooking liquid in the way, a drive shaft, a cam on the drive shaft, said cam having a plurality of irregularities thereon in excess of two, means controlled by said cam for operating said doughnut former and including a follower adapted to engage said cam, said follower causing an operation of the doughnut former when passing each irregularity, variable means for periodically engaging a part movable with said follower to restrain engagement of the follower with certain of said irregularities, a movable control member therefor adapted to occupy a number of positions corresponding to the number of irregularities of said cam and means operated by said control member for operating said variable means to restrain engagement of said cam follower with a certain number of said irregularities when the control member is in one position and with a different number of said irregularities when the control member is in another of its positions.

2. In a doughnut machine in which the doughnuts are progressed along a way, a doughnut former for depositing dough formations in the cooking liquid in the way, a drive shaft, a cam on the drive shaft, said cam having a plurality of irregularities thereon in excess of two, means controlled by said cam for operating said doughnut former and including a follower adapted to engage said cam, said follower causing an operation of the doughnut former when passing each irregularity, latching means for engaging a part movable with said follower to prevent movement thereof while the follower is in position to engage certain of said irregularities, a movable control member therefor adapted to occupy a number of positions corresponding to the number of irregularities of said cam and means operated by said control member for moving said latching means to engage the part movable with said cam follower to permit engagement of the cam follower with a certain number of said irregularities when the control member is in one position and with a different number of said irregularities when the control member is in another of its positions.

3. In a doughnut machine in which the doughnuts are progressed along a way, a doughnut former for depositing dough formations in the cooking liquid in the way, a drive shaft, a cam on the drive shaft, said cam having a plurality of irregularities thereon in excess of two, means controlled by said cam for operating said doughnut former and including a follower adapted to engage said cam, said follower causing an operation of the doughnut former when passing each irregularity, a second shaft, an arm on said second shaft, a plurality of cam followers on said

second shaft, a second cam movable with said first named cam, said second named followers being adapted to engage said second named cam, means operable with said second named shaft for restraining engagement of said first named follower with said first named cam, and means for bringing one of said second named cam followers out of engagement with said second named cam.

10. 4. In a doughnut machine in which the doughnuts are progressed along a way, a doughnut former for depositing dough formations in the cooking liquid in the way, a drive shaft, a cam on the drive shaft, said cam having three irregularities thereon, means controlled by said cam for operating said doughnut former and including a follower adapted to engage said cam, said follower causing an operation of the doughnut former when passing each irregularity, a second shaft, an arm on said second shaft, an engaging member on said arm adapted to engage a part movable with said follower to restrain engagement of the follower with the surface of said cam, a second cam movable with said first named cam, said second named cam having a single irregularity thereon, two cam followers on said second named shaft having operating surfaces disposed in one or more different planes, and means for procuring relative axial movement between the second named followers and the second named cam for procuring operation of the followers with the cam at the various planes of engagement thereof.

15. 5. In a doughnut machine in which the doughnuts are progressed along a way, a doughnut former for depositing dough formations in the cooking liquid in the way, a drive shaft, a cam on the drive shaft, said cam having a plurality of irregularities thereon in excess of two, means controlled by said cam for operating said doughnut former and including a follower adapted to engage said cam, said follower causing an operation of the doughnut former when passing each irregularity, a second cam movable with said first named cam, a second shaft, a plurality of cam followers on said second shaft arranged to engage said second named cam and disposed with their engaging surfaces at one or more different axial localities, means operable with said second named shaft for restraining engagement with first named follower with said first named cam, and means for procuring axial movement between said second named cam and cam followers for bringing any number of cam followers into engagement with said second named cam.

20. 6. In a doughnut machine in which the doughnuts are progressed along a way, a doughnut former for depositing dough formations in the cooking liquid in the way, a drive shaft, a cam on the drive shaft, said cam having three irregularities thereon, means controlled by said cam for operating said doughnut former and including a follower adapted to engage said cam, said follower causing an operation of the doughnut former when passing each irregularity, a second cam movable with said first named cam, said second cam having a single irregularity thereon, a second shaft, an engaging member on said arm adapted to engage a part movable with said first named follower to restrain engagement of the first named follower with the surface of the first named cam, two cam followers on said second named shaft having operating surfaces of different axial extent and adapted to engage the second named cam, and means for procuring relative

axial movement between the second named followers and the second named cam for procuring operation of one or both of said followers with the cam.

7. In a doughnut machine in which the doughnuts are progressed along a way, a doughnut former for depositing dough formations in the cooking liquid in the way, a drive shaft, a cam on the drive shaft, said cam having three irregularities thereon, means controlled by said cam for operating said doughnut former and including a follower adapted to engage said cam, said follower causing an operation of the doughnut former when passing each irregularity, a second cam movable with said first named cam, said second cam having a single irregularity thereon, a second shaft, an engaging member on said second shaft adapted to engage a part movable with said first named follower to restrain engagement of the first named follower with the surface of the first named cam, two cam followers on said second named shaft having operating surfaces of different axial extent and adapted to engage the second named cam, and means for procuring relative axial movement between the second named followers and the second named cam of an extent greater than the aggregate axial extent of the said followers for procuring operation of one or both of said followers with the cam or for moving both of the followers out of engagement with the cam.

8. In a doughnut machine in which the doughnuts are progressed along a way, a doughnut former for depositing dough formations in the cooking liquid in the way, a drive shaft, a cam on the drive shaft, said cam having three irregularities thereon, means controlled by said cam for operating said doughnut former and including a follower adapted to engage said cam, said follower causing an operation of the doughnut former when passing each irregularity, a second cam movable with said first named cam, said second cam having a single irregularity thereon, a second shaft, an engaging member on said second shaft adapted to engage a part movable with said first named follower to restrain engagement of the first named follower with the surface of the first named cam, two rollers on said second named shaft arranged in spaced relation circumferentially and adapted to engage said single irregularity on said second named cam, one of said rollers being longer than the other, and means for procuring relative axial movement between the rollers and the second named cam for procuring operation of one or both of the rollers with the cam.

9. In a doughnut machine in which the doughnuts are progressed along a way, a doughnut former for depositing dough formations in the cooking liquid in the way, a drive shaft, a cam on the drive shaft, said cam having three irregularities thereon, means controlled by said cam for operating said doughnut former and including a follower adapted to engage said cam, said follower causing an operation of the doughnut former when passing each irregularity, a second cam movable with said first named cam, said second cam having a single projecting portion thereon provided with an arcuate surface, a second shaft, an engaging member on said second named shaft adapted to engage a part movable with said first named follower to restrain engagement of said follower with the surface of said first named cam, two cam followers on said second named shaft having operating surfaces

of different axial extent and adapted to engage the second named cam, said second named cam followers being spaced circumferentially a distance apart less than the circumferential extent of said projecting portion of the second named cam, said cam followers when riding on said portion of the second named cam restraining engagement of the follower of the first named cam, and means for procuring relative axial movement between the first named followers and second named cam for causing one or both of said followers to engage said second named cam or to become free therefrom whereby the first named follower is restrained from engaging the first named cam at one or two of said irregularities thereon or is free to engage a. of the said irregularities.

10. In a doughnut machine in which the doughnuts are progressed along a way, movable control means for controlling the rate of travel of the doughnuts along the way, a drive shaft, a cam on said drive shaft, said cam having a plurality of irregularities thereon in excess of two, means controlled by said cam for controlling the operation of said control means and including a follower adapted to engage said cam, variable means for periodically engaging a part movable with said follower to restrain engagement of the follower with certain of said irregularities, a movable control member therefor adapted to occupy a number of positions corresponding to the number of irregularities of said cam and means operated by said control member for operating said variable means to restrain engagement of said cam follower with a certain number of said irregularities when the control member is in one position and with a different number of said irregularities when the control member is in another of its positions.

11. In a doughnut machine in which the doughnuts are progressed along a way, periodically operable control means for controlling the rate of travel of the doughnuts along the way, a drive shaft, a cam on said drive shaft, said cam having a plurality of irregularities thereon in excess of two, means controlled by said cam for operating said control means and including a follower adapted to engage said cam, said follower causing an operation of the control means when passing each irregularity, and latching means for engaging a part movable with said follower to prevent movement thereof while the follower is in position to engage certain of said irregularities.

12. In a doughnut machine in which the doughnuts are progressed along a way, periodically operable control means for controlling the rate of travel of the doughnuts along the way, a drive shaft, a cam on said drive shaft, said cam having a plurality of irregularities thereon in excess of two, means controlled by said cam for operating said control means and including a follower adapted to engage said cam, said follower causing an operation of the control means when passing each irregularity, a second cam movable with said first named cam, a second shaft, a plurality of cam followers on said second shaft adapted to engage said second named cam, means operable with said second named shaft for restraining engagement of said first named follower with said first named cam, and means for bringing one of said second named cam followers out of engagement with said second named cam.

13. In a doughnut machine in which the doughnuts are progressed along a way, periodically operable control means for controlling the rate

of travel of the doughnuts along the way, a drive shaft, a cam on said drive shaft, said cam having a plurality of irregularities thereon in excess of two, means controlled by said cam for operating said control means and including a follower adapted to engage said cam, said follower causing an operation of the control means when passing each irregularity, a second cam movable with said first named cam, a second shaft, a plurality of cam followers on said second shaft adapted to 10

engage said second named cam, means operable with said second named shaft for restraining movement of said first named follower with said first named cam, said second named followers having operating surfaces of different axial extent, and means for procuring relative axial movement between the second named followers and the second named cam for procuring operation of one or both of said followers with the cam.

STEPHEN A. GARDNER.
